(57) **CLAIM**

The ornamental design for a rapid test cup, as shown and described.

DESCRIPTION

FIG. 1 is a front perspective view of a rapid test cup showing our new design;

FIG. 2 is a left side view of a rapid test cup of FIG. 1;

FIG. 3 is a right side view of a rapid test cup of FIG. 1;

FIG. 4 is a rear view of a rapid test cup of FIG. 1;

FIG. 5 is a front side view of a rapid test cup of FIG. 1;

FIG. 6 is a top view of a rapid test cup of FIG. 1;

FIG. 7 is a bottom view of a rapid test cup of FIG. 1;

FIG. 8 is an exploded view of the rapid test cup of FIG. 1; and,

FIG. 9 is a side elevational perspective view of the rapid test cup shown in vertical cross sectional along the longitudinal axis.
